J. A. REY.
TURBO-COMPRESSOR GOVERNING MECHANISM.
APPLICATION FILED APR. 5, 1911.

Patented Apr. 8, 1913.

UNITED STATES PATENT OFFICE.

JEAN ALÉXANDRE REY, OF PARIS, FRANCE.

TURBO-COMPRESSOR-GOVERNING MECHANISM.

1,058,676.

Specification of Letters Patent. Patented Apr. 8, 1913.

Application filed April 5, 1911. Serial No. 619,049.

To all whom it may concern:

Be it known that I, JEAN ALÉXANDRE REY, of 26 Avenue de Suffren, Paris, France, engineer, have invented a new and useful Improvement in Turbo-Compressor-Governing Mechanism, which improvement is fully set forth in the following specification.

This invention has for its object an arrangement for governing turbo-compressors supplied with steam from two sources *i. e.* a turbo-compressor in which a turbine is adapted to work with steam at high as well as at low pressure. The turbine may be such that the high pressure steam does work until it is reduced to the pressure in the condenser without passing through the special wheels reserved for low pressure steam or may be such that the high pressure steam expands first to the pressure of the low pressure steam, then is employed in the same wheels as the low pressure steam until it is reduced to the pressure in the condenser.

This arrangement comprises the combination of the following elements: (a) a valve or like member regulating the admission of low pressure steam; (b) a valve or like member regulating the admission of high pressure steam; (c) mechanism, subjected either to the pressure of the air compressed by the compressor, or to a rise or fall in pressure which depends upon the delivery of the compressor; this mechanism being adapted under the action of the pressures or reduction in pressure to which it is subjected, to operate the valves referred to above in such a manner as to open first the low pressure admission valve then the high pressure admission valve and to close them in the reverse order, the low pressure admission valve having its useful travel after the high pressure admission valve is closed; (d) mechanism subjected to the action of a speed governor and adapted, when the engine goes beyond the normal speed, to act upon the valves to close them only; (e) a second valve or the like in the low pressure pipe; (f) mechanism subjected to the action of the low pressure steam and adapted to close the second low pressure valve when the pressure of said steam falls below a given point and to open it when the pressure of said steam rises beyond a given point. The said elements are combined in such a manner as to insure the constancy, either of the pressure, or of the delivery of

the air compressed by the compressor (and to prevent the turbine racing) whatever may be the variations in pressure of the low pressure steam.

The accompanying illustrative drawing shows diagrammatically one method of carrying out the invention.

The turbine driving the compressor (not shown) is in the drawing divided into two separate parts one of which A is adapted to work with low pressure steam from the pipe *a*; B is the other part adapted to work with high pressure steam from the pipe *b*; both A and B exhaust through the port *c* leading to the condenser.

d is a valve in the pipe *a* and *e* a valve in the pipe *b*. The valve *d* is connected, by a lever *f*, to a rod *g* sliding within a piston *h*, which moves in a cylinder *i*. The cylinder *i* communicates through the pipe *j* with the compressor delivery pipe. The valve *e* is connected by a lever *k* to a sleeve *m* which can slide freely upon the rod *g*; the sleeve *m* is acted upon by a spring *l* which has the piston *h* for abutment and which tends to force the sleeve against a shoulder *n* on the rod *g*.

o o are counterweights acting upon the rod *g* to balance the pressure acting upon the air piston *h*.

The end of the rod *g* passes freely through a piston *p* moving in a cylinder *q*; but this piston can act upon the rod *g* when it moves up through the shoulder *r*; *s* is a spring which tends to move the piston downward.

The cylinder *q* communicates through a pipe *t* with a valve *w* distributing oil under pressure, the movements of which valve allow a pipe *t* to be placed in communication sometimes with a pipe *v* containing oil under pressure, sometimes with an exhaust pipe *x*. The slide valve *w* is actuated by a governor *z* whose speed is proportional to that of the turbine.

1 is a second valve within the pipe *a*, connected to a piston *2* which a spring *3* tends constantly to raise. The lower portion of the piston *2* is in communication through the pipe *4* with the lower face *5* of a differential distributing piston *6* moving within a cylinder *7* comprising two parts of different diameters. This cylinder communicates both through a pipe *8* with the atmosphere and through a pipe *9* and passage *10* with a known type of steam accumulator delivering

low pressure steam and lastly through a pipe 11 with the condenser. The cylinder also has formed in it a passage 12. The differential piston 6 is hung from a regulatable spring 13 and is provided with an annular recess 14.

When at rest, the high pressure valve *e* and the low pressure valve *d* are fully open and the air piston *h* is in its lowest position.

- 10 When at work, if the pressure of the air rises, above the normal, the piston *h* rises and through the intermediary of the rod *g* and the levers *k* and *f* closes the valves *e* and *d*; until the pressure of the air again becomes normal, the piston *h* remains stationary and maintains the valves in a position corresponding to the supply of air required of the compressor.

The turbine may work at high pressure only, or at low pressure only or both simultaneously. For this purpose, the valves are arranged in such a manner that the low pressure valve *d* has an effective movement only when the high pressure valve *e* is closed *i. e.* the low pressure valve *d* has a total travel equal to its effective travel plus the travel necessary to close the high pressure valve.

When working at high pressure only, the regulation acts upon the high pressure valve *e*, the low pressure valve *d* does nothing. When working at low pressure only, the valve *e* is maintained closed by the spring *l*, the rod *g* slides in the sleeve *m* and the regulation acts upon the low pressure valve *d* during its useful travel. For simultaneous working the low pressure valve *d* is full open and regulation is effected by the high pressure valve *e*.

- 40 An oil dashpot consisting of an annular piston 16 and cylinder 17 prevents oscillations.

When the turbine attains a given number of revolutions (for example six per cent. more than normal speed) the centrifugal governor *z* raises the piston *w* which allows oil under pressure to pass beneath the piston *p* thus raising the rod *g* and closing the valves. When the turbine again runs at a normal speed, the governor *z* lowers the distributing piston *w* and the oil under pressure beneath the piston *p* passes to the oil reservoir through the passage *y* and the pipe *x*. The piston *p* which governs the speed limit is independent of the regulation by air and the spring *s* keeps it at its lowest position.

The valve 1 should open when the pressure in the steam accumulator rises to 1.1 kg. for example and close when the pressure falls to 0.8 kg. for example. When the pressure is 1.1 kg. the differential piston 6 of the distributer falls and uncovers the port leading to the pipe 11 which places the lower face of the piston 2 in commun-

cation with the condenser through the pipe 4, the passage 12 and the pipe 11. The pressure of 1.1 kg. acting upon the upper face of the piston 2 opens the valve 1. The lower face 5 of the small piston 6 is now also in communication with the condenser and the distributer can only rise when the pressure in the accumulator acting upon the upper face 15 of the large piston, falls to 0.8 kg. The piston 6 of the distributer will then close the port leading to the pipe 11 which communicates with the condenser and opens the port leading to the passage 10 which will place the piston 2 in communication with the accumulator through the pipe 4 passages 12 and 10 and the pipe 9. The piston 2 having a like pressure on its two faces, the valve 1 closes by the action of the spring 3. The lower face 5 of the small piston of the distributer now raised, is placed in communication with the accumulator, and the distributer will fall when the pressure in the accumulator acting upon the upper face 15 of the large piston has risen to 1.1 kg.

The arrangement described and shown effects the regulation of a turbo-compressor so as to insure a constant pressure of air. If it be desired that the regulation shall take place so as to insure a constant delivery of air, the piston *h* must be acted on through the pipe *j* not by the pressure of the compressed air but by a pressure (or a fall in pressure) dependent on the delivery of air by the compressor. For this purpose there is used for example known apparatus which causes an increase or decrease in pressure depending on the delivery.

Claims.

1. In a turbo-compressor, valves for controlling the admission of high and low pressure steam, in combination with fluid pressure mechanism for regulating said valves and arranged to open first the low-pressure valve and then the high pressure valve, a governor and mechanism operated by the same to close said valves, a second low-pressure valve, and mechanism arranged to close said valve when the pressure of the steam falls below a stated limit.

2. In a turbo-compressor working with both high pressure and low pressure steam the combination with means regulating the inlet of high pressure and low pressure steam, of fluid pressure mechanism for regulating said means and adapted to be operated by the compressed air and arranged to open first the low pressure valve and then the high pressure valve, a governor and mechanism operated thereby to close the said valves, a second low pressure valve and mechanism arranged to close said valve when the steam pressure falls below a given limit.

3. In a turbo-compressor working with both high and low pressure steam, the means

- controlling the high and low pressure steam valves comprising a pressure actuated piston and means for actuating the same, a rod which can move with respect to the piston whose movement operates the said valves, a second piston adapted to move said rod in one direction only, and means operated by a governor for supplying fluid to said second piston.
- 10 4. In a turbo-compressor working with high and low pressure steam the means for controlling the supply of low pressure steam comprising a valve operated by a piston one face of which is in constant communication with the low pressure steam and the other face, sometimes with the low pressure steam and sometimes with the condenser, a cylinder communicating with the steam supply
- and a differential piston adapted to operate by the rise or fall in pressure of said steam, 20 arranged within the cylinder, means for allowing atmospheric pressure to act on said differential piston, and steam ducts communicating with the steam supply and the condenser on the one hand, and with the said 25 other face of the valve operating piston on the other, said ducts being adapted to be alternately opened by the differential piston.
- In testimony whereof I have signed this specification in the presence of two subscribing witnesses.
